UNITED STATES PATENT OFFICE

SAMUEL E. GUINN, OF JOHNSON CITY, TENNESSEE

DESIGN FOR A HUMIDOR

Application filed October 30, 1930. Serial No. 37,448. Term of patent 3½ years.

To all whom it may concern:

Be it known that I, SAMUEL E. GUINN, a citizen of the United States, residing at Johnson City, in the county of Washington and State of Tennessee, have invented a new, original, and ornamental Design for a Humidor, of which the following is a specification, reference being had to the accompanying draw-

ings, forming part thereof, and in which—

Fig. 1 is a perspective view of the humidor showing my new design.

Fig. 2 is a plan view.

I claim:

The ornamental design for a humidor, as shown.

SAMUEL E. GUINN.
